UNITED STATES PATENT OFFICE

2,512,062

SADIRON

Russell I. Huffman, Dover, Ohio, assignor, by
mesne assignments, to Knapp-Monarch Com-
pany, St. Louis, Mo., a corporation of Delaware

Application July 2, 1946, Serial No. 680,925

2 Claims. (CL 219—25)

1

My present invention relates to a sad iron having a number of features which make the iron desirable from the housewife's standpoint and comparatively inexpensive from the manufacturer's standpoint.

One object of the invention is to provide an iron which has a relatively cool top, the top member of the iron being formed of Bakelite or the like, and this top member being connected to the sole plate by means of a plurality of spaced 10 apart plates between which air may circulate to prevent the high temperature of the sole plate being directly conducted to the top member of the iron.

Another object is to provide the top member with fluting or other surface irregularities which minimize contact with the operator's fingers or hand when accidentally touching the iron, thus further reducing the possibility of receiving a burn.

Still another object is to provide a sad iron structure which has side wings for the purpose of permitting the iron to lie on its side instead of up-ending it rearwardly in the normal manner when the iron is laid aside during the ironing process.

A further object is to provide a handle for the iron attached to the top member thereof, and to provide a simple means of securing the top member in position by a hook at the front end of the iron and a single screw at the rear end thereof, the top member, after the screw has been removed being slidably endwise for engaging the hook.

Still a further object is to provide an arrangement which permits the use of a relatively large dial for easy reading of the indicia thereon, and to provide means for illuminating the dial to aid in the reading of such indicia.

An additional object is to provide a connection between the dial and the thermostat of the iron that minimizes heat conduction from the thermostat to the dial and consequently to the knob that is used for operating the dial, thus keeping the knob cool enough to adjust without any discomfort as in the usual types of thermostat where the knobs are directly connected to the thermostat adjusting screws and which knobs attain a relatively high temperature in spite of the fact that they are made of insulating material.

A further object is to provide a bushing on the thermostat operating shaft which may be removed for permitting endwise sliding of the top member of the iron during disassembly and

2

which prevents wobble of the thermostat shaft and dial when the iron is assembled.

Further additional objects are to provide an arrangement of parts in a sad iron which permit of relatively easy assembly and to provide a sole plate having a concave portion permitting the possibility of getting the sole plate close around collars of shirts and similar curved surfaces for proper ironing thereof.

With these and other objects in view, my invention consists in the construction, arrangement and combination of the various parts of my device whereby the objects contemplated are attained, as hereinafter more fully set forth, pointed out in my claims, and illustrated in the accompanying drawings, wherein:

Fig. 1 is a plan view of a sad iron embodying my present invention, a portion of the handle being broken away to show the sight window 15 for the thermostat dial and the thermostat knob.

Fig. 2 is a vertical sectional view on the line 2—2 of Fig. 1.

Fig. 3 is a vertical sectional view on the line 3—3 of Fig. 2.

Fig. 4 is a bottom plan view of the thermostat dial per se.

Fig. 5 is a plan view of the sole plate of the iron showing the thermostat thereon and the terminal bars which extend upwardly for connection to the service cord.

Fig. 6 is a similar plan view showing a casing member and a pair of plates added to Fig. 5, and also the thermostat dial and its illuminating light added thereto.

On the accompanying drawing I have used the reference numeral 10 to indicate a sole plate. The sole plate 10 has imbedded therein the usual coiled resistance wire 12 surrounded by insulating material 14 to constitute a heating element for the sole plate. On the sole plate a thermostat 15 of ordinary construction is provided and the thermostat is held in position by a strap 16.

Over the heating element a sheet metal casing 18 is provided, and above the casing 18 heat radiator plates 20 and 22 are shown, spaced from each other and from the casing 18. The spacing is accomplished by means of projecting bosses 24 riveted together as at 26. The assembly of casing 18 and heat radiator plates 20 and 22 is then held in position by a pair of screws 28 (see Fig. 3) threaded into the strap 16, the strap being provided with a pair of threaded openings 30 for this purpose.

A top member 32 is provided to cover the heat radiator plate 22, and this top member is pre-

ferably made of Bakelite or similar insulating material. Secured to the top member 32 is a handle 34, there being provided a single screw 36 adjacent the front end for fastening the two together. The assembly of top member 32 and handle 34 is then secured to the heat radiator plate 22 by means of a hook 38 secured as by a screw 40 to the front of the top member 32, and a single screw 42 adjacent the rear end of the handle.

The plate 22 has a square opening 44 to receive the hook 38 after the forward end of the hook has been inserted through the square opening and then pushed forwardly to position shown in Fig. 2. When in this position the screw 42 is then inserted thru a cover plate 41 for the rear end of the handle and threaded into a bracket 48 secured to the plate 22.

The plate 46 covers a ball member 50 through which a flexible sleeve 52 extends for the service cord 54 as shown in my co-pending application Serial No. 741,474 filed April 15, 1947.

The service cord 54 is connected as shown in Fig. 2 to terminal brackets 55 and 58 for the thermostat 15 and the heating element 12 in series with each other in the usual manner. A terminal bracket 60 is also provided for the heating element, the brackets 59 and 60 being connected with the ends of the heating element and an indicator light 62 shunting these terminals as by connection thereto through wires 64 and 66.

A socket 68 is provided for the indicator bulb 62. The socket 68 and the wires 64 and 66, as well as the bulb 62 are not subjected to excessive heat because of the cooling effect of air passing between the casing 18 and the plate 20, and between the plates 20 and 22, and therefore can be of ordinary construction whereas if they were located in the usual iron shell the temperature would be too high.

For adjusting the thermostat 15 I provide a control knob 70 mounted on a thermostat shaft 72. The shaft 72 is connected to a dial 74 and the dial in turn is connected to the thermostat adjusting screw 76 by a bracket 78. The upper end of the screw 76 is fluted so that the dial can be adjusted to the proper position thereon, and the bracket 78 provides a spacing between the screw 76 and the dial 74 that minimizes heat transmission from the thermostat to the knob 70. The knob, therefore, remains comparatively cool so it can be adjusted with comfort, and the dial 74 is also comparatively cool so that its surface is not discolored by heat. Accordingly the dial can be enameled white or some other suitable color with lettering such as shown in Fig. 6 provided thereon as the indicia for determining the position of the thermostat. The indicator light 62 it will be noted, is close to the edge of the dial so as to illuminate it and by shunting the heating element in the iron, the light is only on when the heating element is on.

A sight opening 80 is provided in the top member 32 through which the dial can be seen and the sight opening may be covered as by a piece of glass or transparent glass 82.

The top member 32 has an enlarged opening 84 surrounding the thermostat shaft 72 as shown in Fig. 2, and this is filled with a bushing 86 to prevent wobble of the shaft 72. During disassembly of the iron, after the knob 70 is removed from the shaft 72 as by loosening the set screw 88, the bushing 84 may be removed so that the top member 32 can be shifted for unhooking the hook

38 from the edge of the opening 44. Thus assembly and dis-assembly is facilitated, and at the same time a good bearing is provided for the thermostat shaft in the form of the bushing 86.

The top member 32 as shown in Fig. 1 is fluted, or may be provided with other types of surface irregularities as indicated at 90, so that if the top member is accidentally touched by the fingers or the hand, the usual area of touch is minimized, thereby reducing the possibility of becoming burned by the top of the iron. Additionally, the top is kept relatively cool by reason of the air through which the iron passes carrying away heat from the casing 18 and the radiator plates 20 and 22.

The top member 32 is provided with side wings 92 which may be formed of heavy wire or rod material and attached thereto as by rivets 94 shown in Fig. 3. The wings 92 are so positioned that the iron can be laid on its side instead of up-ended rearwardly as is usual in connection with sad irons. When lying on its side the line of contact will be as shown by the dash lines 96 in Fig. 3, the iron thereby being adaptable for lying on either the left side or the right side. Less motion and less lifting of the iron is required by this method of laying the iron aside, than by the "up-ended" method.

My construction with its "side lay" feature just described further lends itself to the provision of an inwardly curved surface indicated at 98 for the sole plate 10. Such surface permits close ironing around collars of shirts and similar curved surfaces thereby increasing the efficiency of the iron.

From the foregoing description it will be obvious that I have provided a sad iron having a number of desirable features. The top of the iron remains comparatively cool, and the use of side wings 92 permits laying of the iron on its side when not in use. The assembly of the parts has been simplified considerably. An easily readable dial due to its comparatively large size and the illumination thereof is provided without unnecessarily complicating the structure of the iron. The sole plate is so designed that it may iron closely adjacent curved surfaces with a maximum of contact due to the concave character of the portion 98 of the sole plate, whereas in most irons the edges of the sole plates are convex.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In an iron structure, a sole plate, a housing therefor, a top member for said housing, a handle on said top member, said top member having means of coaction with said housing which is operative to connect the two together when the top member is placed on the housing and moved in one direction, a screw cooperating between said handle and said housing for connecting the two together and for moving said top member in said direction, said top member having an enlarged opening, a thermostat on said sole plate having a shaft extending upwardly through said enlarged opening, a sleeve for journaling said shaft, said sleeve being removably positioned in said enlarged opening whereby when said sleeve is removed, said top member may be shifted in a direction opposite said direction and

said screw may be removed for disconnecting said top member from said housing

2. In an iron structure of the character described, a sole plate, a housing therefor, a top member for said housing, a handle on said top member, said top member having an enlarged opening and means of coaction with said housing which is operative to connect the two together when the top member is placed on the housing and moved in one direction, a second means of cooperation between said handle and said housing for connecting the two together and moving said top member in said direction, a thermostat on said sole plate having a shaft extending upwardly through said enlarged opening, a sleeve 15 for journalling said shaft, said sleeve being removably positioned in said enlarged opening, and a knob on said shaft to adjust said thermostat and keep said sleeve in said opening.

RUSSELL I. HUFFMAN.
